UNITED STATES PATENT OFFICE.

HERBERT J. LONG, OF NEW BRUNSWICK, NEW JERSEY, ASSIGNOR TO THE LONG-LANDRETH-SCHNEIDER COMPANY, OF NEW BRUNSWICK, NEW JERSEY.

DESIGN FOR A WATER-HEATER.

47,960.

Specification for Design.

Patented Oct. 12, 1915.

Application filed July 26, 1915. Serial No. 42,096. Term of patent 14 years.

To all whom it may concern:

Be it known that I, HERBERT J. LONG, a citizen of the United States, residing at New Brunswick, in the county of Middlesex and State of New Jersey, have invented a new, original, and ornamental Design for Water-Heaters, of which the following is a specification, reference being had to the accompanying drawing, forming part thereof.

Figure I is a front elevation of a water

heater embodying my invention. Fig. II is an end elevation of the same.

I claim:

The ornamental design for a water heater as shown.

HERBERT J. LONG.

Witnesses:

W. H. FRENCH,
GEO. H. VAN VECHTEN.
